UNITED STATES PATENT OFFICE.

JENNINGS B. STOCKHAM AND JOHN B. HICKMAN, OF BROKEN BOW, NEBRASKA.

DESIGN FOR A COMBINED DISPLAY AND ADVERTISING SIGNBOARD.

Application filed July 26, 1927. Serial No. 22,883. Term of patent 3½ years.

To all whom it may concern:

Be it known that we, JENNINGS B. STOCKHAM and JOHN B. HICKMAN, citizens of the United States, residing at Broken Bow, in the county of Custer and State of Nebraska, have invented a new, original, and ornamental Design for a Combined Display and Advertising Signboard, of which the following is a specification, reference being had to the

accompanying drawing, forming part thereof.

The figure is a view in perspective of a combined display and advertising signboard, embodying our design.

We claim:

The ornamental design for a combined display and advertising signboard, as shown.

JENNINGS B. STOCKHAM.

JOHN B. HICKMAN.
